UNITED STATES PATENT OFFICE.

CHARLES E. GODLEY, OF DETROIT, MICHIGAN, ASSIGNOR TO EDMUNDS AND JONES MANUFACTURING COMPANY, OF DETROIT, MICHIGAN, A CORPORATION OF MICHIGAN.

CONNECTOR.

1,108,165.

Specification of Letters Patent. Patented Aug. 25, 1914.

Application filed March 9, 1914. Serial No. 823,316.

To all whom it may concern:

Be it known that I, CHARLES E. GODLEY, a citizen of the United States, and a resident of Detroit, in the county of Wayne 5 and State of Michigan, have invented a new and Improved Connector, of which the following is a specification.

This invention relates to means for connecting a plurality of series of electric circuits, and its object is to provide a device of this type especially adapted to connect feed wires to the bodies of electric lamps which are supplied with a plurality of lighting filaments.

15 Large numbers of electric lamps of the headlight type are at present being manufactured with two electric light filaments, usually of different candle power, mounted in either one or two bulbs, the filament of 20 higher candle power being placed at the focal center of the reflector, so that its rays will be projected in parallel lines, and that of lower candle power being placed away from and preferably above the focal center, so 25 that its rays will be projected divergently, so that a mild diffused light will issue from the lens, which light will not be blinding to pedestrians. The first filament is especially adapted for country and the second for city driving.

This invention consists of a normally fixed sleeve of metal of novel design having a pair of novel binding posts, together with a novel plug of insulating material having 35 means to receive three wires, one for each of the binding posts and the third for the metal sleeve.

In the accompanying drawing, Figure 1, is an elevation of this improved connector 40 mounted in the body of an electric headlight. Fig. 2 is an elevation of the other side. Fig. 3 is a central longitudinal section of this connector. Fig. 4 is a similar section at right angles to the section of Fig. 45 3. Fig. 5 is a section on the line 5—5 of Fig. 3.

Similar reference characters refer to like parts throughout the several views.

The lamp body 1, reflector 2 and lens 3, 50 shown in the drawings may be of any desired construction. In the reflector is a sleeve 4 to receive the socket 5 of a light bulb 6, having a high power filament whose heated portion 7 is at the focal center of 55 the reflector, and a low power filament

whose heated portion 8 is at one side, preferably above the focal center. One wire 9 to the high power filament connects to the circuit 10, and one wire 11 of the low power filament connects to the circuit 12. The 60 wires 13 and 14 of these filaments may be grounded on the sleeve 4, or wherever else desired. It will be understood that it is not necessary to have both filaments in one bulb, many lamps being provided with two 65 independent bulbs, each having one wire from the filament grounded on the reflector.

A sleeve 16 is shown connected into the body and is therefore grounded. In this sleeve is removably secured the metal cylindrical shell 17, by means of the screw 18. Within the shell is a cylinder 19 of insulating material such as hard rubber or indurated fiber, having a central tongue 20 that separates the binding posts 22. These 70 posts have rectangular outer ends 23 provided with holes 24 to receive the circuit wires within the lamp body, and with the screws 25 to hold the wires 10 and 12.

On the outer ends of the posts are heads 80 26 and on the posts are the springs 27 which force the posts outwardly. The shell is formed with notches 28 and 29, a tongue 30 projecting into one of the notches as shown in Fig. 1. The shell and the parts mounted 85 therein constitute the female member of the connector.

The male member of the connector is a plug or cylinder 33 of insulating material, having a circumferential collar 34, and longitudinal passages in which are seated the metal bars 35, 36 and 37. The outer end of this cylinder may be threaded to receive a cap 38, also of insulating material. The bars are all formed with sockets 39 to receive 90 the wires 40, 41 and 42, the screws 43 securing the wires in position. The ends of the bars 36 and 37 are flush with or protrude slightly from the end of the member 33 and engage the ends of the posts 22. The third bar 38 cuts through the cylindrical surface of the plug 33 and is cut down to form a continuous surface therewith, as shown in Figs. 3 and 5. A pin 45 is shown extending entirely through this bar and the plug, its ends 105 projecting about the thickness of the shell, 17. A second pin 46 also projects from the bar. The wire 42 may lead to a contact 47 and the wire 41 to a contact 48, while the wire 40 leads to a current source 50, which is 110

in turn connected to the switch 51 by wire 52. The wires 10 and 12 leading to the filaments are connected to the posts 22 by means of the screws 25, and the female member of 5 the connector is then properly mounted in the sleeve 16, after which the lamp is ready for shipment. After being mounted on the vehicle or wherever else it is to be used, the proper wires 40, 41 and 42 are connected to 10 the plug 33. This plug is then inserted in the shell 17 with the two pins 45 and 46 passing into the notch 28, until the ends of the bars 36 and 37 press the posts 22 outwardly, after which the plug is turned to carry the 15 ends of the pin 45 into the downturned ends of the notches 28 and 29, as shown in Figs. 1 and 2. The springs 27 will hold this pin in these downturned ends and thus prevent the plug from turning. The pin 46 prevents 20 the plug being locked in the shell except when this pin is in the notch 28. The pin 45 insures a good connection between the shell and the bar 35, that is, between the body of the lamp and the wire 40.

25 I claim:

1. In a connector for electric wires the combination of a female member consisting of a metal shell, a core of insulating material, a binding post slidably mounted in the 30 core, and a spring to normally hold the post inwardly; and a male member fitting within

the shell and consisting of a body of insulating material, a plurality of posts mounted in the body, each formed to receive the end of a wire, one of the posts contacting with the shell and the other contacting end to end with the binding post; and means to secure the members together.

2. In a connector for electric wires, the combination of a female member consisting of a metal shell adapted to connect into an electric circuit, a core of insulating material within the shell, a pair of binding posts slidably mounted in the core, and springs on said posts; and a male member fitting within the shell and consisting of a cylinder of insulating material, a series of posts mounted in said cylinder, each formed to receive an end of a wire, one of the posts contacting with the shell and the other two contacting with the adjacent ends of the spring pressed posts; said shell formed with notches, and a pin carried by the cylindrical male member adapted to engage in the notches to secure the members together.

In testimony whereof I have signed this specification in the presence of two subscribing witnesses.

CHARLES E. GODLEY.
